United States Patent Office

Des. 187,967

Patented May 17, 1960

187,967

TUBE FURNACE

Percival B. Crocker, Foxboro, Mass., assignor to The Sentry Company, Foxboro, Mass., a corporation of Massachusetts

Application January 8, 1960, Serial No. 58,966

Term of patent 14 years

(Cl. D81—1)

Fig. 1.

Fig. 2.

Fig. 1 is a front perspective view showing the right side of a tube furnace embodying my new design; and

Fig. 2 is a front perspective view showing the left side thereof.

The rear not shown is substantially a mirror image of the front shown.

I claim:

The ornamental design for a tube furnace, substantially as shown and described.
